UNITED STATES PATENT OFFICE

HERBERT H. GRUBB, OF BARABOO, WISCONSIN, ASSIGNOR TO HUMANE STANCHION WORKS, OF BARABOO, WISCONSIN, A CORPORATION OF WISCONSIN

SWING

Application filed January 27, 1930. Serial No. 423,610.

This invention relates to an improvement in swings of the type in which a plank or swing board is pivotally supported at spaced points and usually adjacent its ends by means of links or hanger rods, the lower ends of which are pivotally connected to the plank and the upper ends of which are pivotally suspended from suitable supports so that the swing board while remaining horizontal may swing back and forth in a path paralleling its long dimensions.

One of the principal objects of the present invention is to simplify and strengthen a swing of this character, to enhance its capacity to afford healthful and exhilarating recreation and exercise for children, and to minimize the possibilities of the users of the swing being injured.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a view in end elevation showing a swing constructed in accordance with the present invention;

Figure 2 is a view thereof in longitudinal vertical section taken in the plane of line 2—2 of Figure 1;

Figure 3 is a detail view in vertical section taken on line 3—3 of Figure 1, parts being shown in elevation for the sake of illustration;

Figure 4 is a detail view in horizontal section taken on line 4—4 of Figure 1, with parts shown in elevation for the sake of simplicity in illustration; and

Figure 5 is a similar view taken on line 5—5 of Figure 2.

Referring to the drawings it will be seen that the swing embodying the present invention includes a pair of spaced supports or end frames designated at 1 and 2 and of inverted U-shape. The end frames 1 and 2 are of identical construction and, as clearly shown in Figure 1, each has spaced vertical legs 3 connected by an integral arch-like upper por-

tion 4. Suspended from each end frame or support is a U-shaped hanger, the hanger suspended from the end frame 1 being designated at 5 and the hanger being suspended from the end frame 2 being designated at 6. The hangers 5 and 6 are of identical construction and each has spaced side rods or hanger rods 7 connected at their lower ends by an integral and horizontally disposed connecting portion 8. The horizontal portion 8 of each hanger is engaged beneath spaced portions of a swing board or plank 9. Bearing straps 10 embrace the horizontal portions of the hanger rods below the swing board and are connected to the swing board by means of fastening devices 11 thereby pivotally interconnecting the swing board and the hangers. The upper ends of the spaced side rods of each hanger are pivotally connected as at 12 to connecting brackets 13 clamped and otherwise suitably secured to the arched portions of the supports 1 and 2.

The supports 1 and 2 are braced and strengthened by means of longitudinal connecting rods 14, there being one such connecting rod 14 at each side of the swing. Each connecting rod 14 is alined with the legs 3 of the end frames 1 and 2 with which it is associated and is fastened at its ends to these legs by the fittings 15 shown in detail in Figures 3 and 4. As shown, each fitting 15 is of two-part construction, the parts being adapted to form a socket 16 for the end of the connecting rod 14 which the fitting receives. Bolts and nuts 17 secure the parts of each fitting 15 together and to the leg 3 of the frame with which it is associated. Braces 20 are provided between each leg 3 of the supporting frame and the adjacent portion of the rod 14 connected thereto, these braces 20 being extended at an angle as shown in Figure 2 and being connected to the rod 14 and to the legs 3 by bolts and nuts 21 and connecting fittings 22 as shown in detail in Figure 5.

The arched type end frames 1 and 2 are each constructed of a single piece of metal and may be tubular. This end frame construction has substantial inherent strength and when the end frames are suitably interconnected and braced a very rigid and durable

construction is provided. Further than this, the arched portions of the end frames are utilized to directly pivotally support the hangers for the swing board and as a consequence the swing board and the hangers, when swinging back and forth, are spaced a substantial distance from the vertical legs of the supporting frames, thus avoiding danger of the children riding the swing board striking the rigid supporting frames. Another advantage resides in having end supporting frames which permit the use of hangers including parallel side rods spaced apart approximately the same distance as the lateral dimension of the swing board. This enables the child or person riding the swing board to grasp the hanger rods and propel the swing with a pumping effect thereby increasing the opportunity for exercise as well as enhancing the enjoyment of the user.

The invention claimed is:

1. A swing of the character described comprising spaced supports, each including transversely spaced legs and an arched connecting portion integral with and extending between the legs, longitudinal connecting elements extending in the plane of and secured to the legs of the supports, a swing board extending longitudinally between and centrally of the supports and U-shaped hangers having their lower ends pivotally connected to the swing board and having their upper ends pivotally connected to the arched portions of the support.
2. A swing of the character described comprising spaced supports, each including a pair of transversely spaced vertical legs and an arched connecting portion integral with the legs, a pair of hangers, one for each support, each hanger comprising a pair of vertical and parallel hanger rods having their upper ends pivotally connected to the arched portion of their support adjacent the center of the support, and a swing board extending longitudinally and centrally of the supports and pivotally connected to and supported upon the lower ends of the hanger rods.

In witness whereof, I hereto affix my signature.
